CLAIM

I claim the ornamental design for a thermostat, as shown and described.

DESCRIPTION

FIG. 1 is a top left perspective view of a thermostat according to the claimed design;

FIG. 2 is a top right perspective view of the claimed design of FIG. 1;

FIG. 3 is a front view of the claimed design of FIG. 1;

FIG. 4 is a rear view of the claimed design of FIG. 1;

FIG. 5 is a top view of the claimed design of FIG. 1;

FIG. 6 is a bottom view of the claimed design of FIG. 1;

FIG. 7 is a right side view of the claimed design of FIG. 1; and,

FIG. 8 is a left side view of the claimed design of FIG. 1. The broken lines depict portions of the thermostat that form no part of the claimed design.
